UNITED STATES PATENT OFFICE.

LOUIS C. WOEHNING, OF NEW YORK, ASSIGNOR TO PAULINE L. RUTHENBURG, OF BROOKLYN, N. Y.

IMPROVEMENT IN SIZE-MARKS FOR HATS.

Specification forming part of Letters Patent No. **89,108**, dated April 20, 1869.

To all whom it may concern:

Be it known that I, LOUIS C. WOEHNING, of the city and State of New York, have invented and made a certain new and useful Improvement in Hatters' Size-Marks; and I do hereby declare the following to be a full, clear, and exact description of the said invention, reference being had to the annexed drawing, making part of this specification, wherein—

Figure 1 is a perspective view of the face of the said size-mark, and Fig. 2 is a similar view of the same at the rear.

Similar marks of reference denote the same parts.

The size-marks for hats have usually been made of paper, with the number printed thereon, and this has been gummed to the inside of the hat. It is unsightly, and frequently becomes detached. Metal numbers have also been employed; but they are costly and conspicuous, and generally indistinct.

The nature of my said invention consists in a metal frame having points that turn down to secure a paper or printed number into the metal frame, and also penetrating-points, by means of which the frame and size-number can be attached to the sweat or lining of the hat.

My article is neat and ornamental; it makes a permanent attachment of the size-number to the hat or cap, and one metal frame answers for any size-number, and thereby the manufacture and use are facilitated.

In the drawing, *a* is a small metal frame. I prefer an oval shape. *b b* are points or lips projecting from the edge of the frame, to be folded over at the back and secure the number *c*, that is a piece of paper or card with the number printed thereon. The points *d*, projecting from *a*, are to be thrust through the lining or hat-sweat and bent over to secure the size-mark in place.

My improved hatter's size-mark is a new article of manufacture.

What I claim, and desire to secure by Letters Patent, is—

The hatter's size-mark, formed of a metal frame, with points to secure the number in the frame, and points to attach the frame to the hat, as set forth.

In witness whereof I have hereunto set my signature this 5th day of February, A. D. 1869.

LOUIS C. WOEHNING.
